CLAIM

The ornamental design for an adjustable table for attachment to an automobile tailgate, as shown and described.

DESCRIPTION

FIG. 1 is a perspective view of an adjustable table for attachment to an automobile tailgate showing my new design, with the unitary leg in open position for use; FIG. 2 is a bottom plan view with the single leg folded and retracted.

FIG. 3 is a side elevational view on a reduced scale, the opposite side being a mirror image thereof.

FIG. 1

FIG. 2

FIG. 3
